(57) **CLAIM**

The ornamental design for a baffle for a crankcase filter assembly, as shown and described.

DESCRIPTION

FIG. 1 is a top perspective view of our baffle for a crankcase filter assembly;

FIG. 2 is a bottom perspective view of our baffle for a crankcase filter assembly;

FIG. 3 is a top plan view of the baffle of FIG. 1;

FIG. 4 is a bottom plan view of the baffle of FIG. 1;

FIG. 5 is a left side elevation of the baffle of FIG. 1;

FIG. 6 is a right side elevation of the baffle of FIG. 1;

FIG. 7 is a front elevation of the baffle of FIG. 1; and,

FIG. 8 is a rear elevation of the baffle of FIG. 1.

The broken line showing of portions is included for the purpose of illustrating environment and forms no part of the claimed design for a baffle for a crankcase filter assembly.
